UNITED STATES PATENT OFFICE.

BARTON D. HUNTING, OF ROCKFORD, MICHIGAN.

WELL-COVER.

1,197,206.

Specification of Letters Patent.

Patented Sept. 5, 1916.

Application filed August 24, 1914. Serial No. 858,323.

To all whom it may concern:

Be it known that I, BARTON D. HUNTING, a citizen of the United States, residing at Rockford, in the county of Kent and State of Michigan, have invented certain new and useful Improvements in Well-Covers, of which the following is a specification.

My invention relates to improvements in covers for wells, cisterns, &c., and its objects are: First, to provide a means whereby the pump and its connections may be readily removed and replaced without the necessity of removing or replacing the entire cover. Second, to provide a means whereby pump bases of different diameters may be readily connected with the cover. Third, to provide a means whereby the larger portion of the cover may be removed and replaced without touching or disturbing the cover to which the pump is attached, and, fourth, to provide a means whereby I can insure a close, tight, non-leakable cover for a cistern or well. I attain these objects by the mechanism and construction shown in the accompanying drawings, in which:

Figure 1 is a plan of the curb or base with the covers removed. Fig. 2 is the same with the covers in place. Fig. 3 is a transverse section of the base on the line $\alpha\alpha$ of Fig. 1. Fig. 4 is a longitudinal section of the base and covers on the line yy of Fig. 2, showing the base and covers in place at the top of a well. Fig. 5 is a bottom plan of the larger cover, and Fig. 6 is a plan of the cover to which the pump is secured.

Like characters refer to similar parts throughout the several views.

In the construction of this cover I make a broad base or flange 1 with an upwardly extending rim 2 that is so constructed as to form a large opening, as 7, at one end, and a small opening, as at 6, at the other end. The large opening, 7, should be of sufficient size, diametrically, so a man could easily pass through it to gain access to the inside of the well, and the small opening may be made of any desired size consistent with its ready and safe application and support above the opening. The rim 2 should be provided with a series of outwardly extending lugs 3 that are designed to pass outward upon, or into the concrete 10 so as to insure a perfect connection between the flange 1, the rim 2, the lugs 3 and the concrete 10, and to insure the perfect support of the base even though it was not feasible to support

it upon the top of the well curb 11, as shown in Fig. 4. I also place a series of lugs 4 in the smaller opening, 6, in proper positions to receive the bolts or screws aa for securely connecting the cover 14 to the rim 2. This cover is provided with a series of holes, a' and b' , the former being in proper positions to be made to register with the corresponding holes through the lugs 4, for the purpose of receiving the bolts a and securing the cover to the rim, as hereinbefore suggested, and the holes b' are designed to receive similar bolts that are passed through the slides or clamps 13 to secure said slides firmly to the cover 14 so that the inner ends of said clamps may be made to engage and securely hold the base 12 of the pump body to the cover 14. The cover 14 has an opening 15 that is so arranged that the lower part of the pump body, and the well pipe 18 may be readily passed from the large opening 7 to the center of the opening 15, or as readily removed therefrom for placing or removing the pump as desired. The slides or clamps 13 have slots dd formed in them so they may be adjusted longitudinally to adopt them to different diameters of pump bases without the necessity of boring an unnecessary number of holes through the cover 14.

The cover 14 should be a trifle thicker than the cover 16 so that when the cover 16 is placed onto the base the edge will pass freely between the edge of the pump base 12 and the top of the brackets 5, and when in place can be readily revolved a short distance to carry the lug 9 on the cover 16 under the lug 8 on the base to lock the cover 16 in place so it cannot be raised directly upward to open the passageway 7.

The lug 9 is integral with the lower edge of the rim e of the cover 16, and projects outward therefrom, as indicated in Figs. 4 and 5, and the lugs c are integral with the body of the cover and are designed to hold the cover steady as it is being turned around to force the lug 9 below the lug 8, as hereinbefore stated. The distance between the points 5, in Fig. 1, should be about the same as the opening at 15 in Fig. 6 so the pump pipes, &c., may be made to pass through to position in the opening 15, freely and without difficulty.

The germ of my invention, in this instance, lies in the detachable nature of the cover 14, and the means for securing the

clamps or slides 13 to it, and of making the said clamps longitudinally adjustable to accommodate pump bases of different diameters, though other important elements enter into the invention, as will be pointed out in the claims. This appliance, base and covers, are made, preferably, of cast iron, as this is more easily molded into form and is much less destructive than any other material, and is better adapted to sustain the heavy weight of the concrete filling than any other available metal. One of the principal advantages gained by this construction of cover is that the cover or base 14 may be readily removed from the main base 1 by simply removing three or four bolts *a a*, and various forms and sizes of pump bases, 12, may be fitted to the cover or base 14 by either taking advantage of the slots in the clamps 13, or by shifting the clamps from the position they occupy in Fig. 2 to the position occupied by the bolts *a a*, so that a large margin of adjustment is provided for the position of the clamps 13, as the size of the pump base may require.

What I claim as new, and desire to secure by Letters Patent of the United States, is:

1. In a well cover, a metallic base having an upwardly projecting rim thereon, lugs formed on the upper ends of the rim, said rim forming an opening that is large at one end of the base and small at the other end of the base, a cover for the small end of the opening, said cover open in the center and one edge, bolts for securing this cover to the small end of the rim, a pump base

supported on this cover, adjustable clamps secured to this cover for securing the pump base thereto, a cover for the large opening, 40 and secured by sliding one edge between the pump base and the brackets on the base rim and interlocking the other edge of the cover with a lug on the rim of the base.

2. In a well cover, a base having an upwardly extending rim surrounding an opening that is large at one end and small at the other end, said rim forming two incomplete circles of different sizes, lugs projecting outward and inward from the edge 50 of said rim, a cover bolted to the edge of the small portion of said rim and having an opening from one edge to and beyond the center, clamps adjustably secured to said cover for securing a pump base thereon, a 55 cover for the larger opening in said base, and means for securing said cover by engaging with the pump base at one edge and with a lug on the rim at the opposite edge of the cover.

3. In a well cover, an open metallic base, a cover bolted to the base over one end of the opening, longitudinally adjustable clamps bolted to said cover to secure a pump base thereto, a cover for the other end of 65 said opening, and means for temporarily securing said cover to the base.

Signed at Grand Rapids, Michigan, August 20, 1914.

BARTON D. HUNTING.

In the presence of—

I. J. CILLEY,
DONALD T. HUNTING.
